APPLIQUE EMBLEM OR SIMILAR ARTICLE

Richard E. Thompson, San Diego, Calif., assignor to The San Diego Hockey Club, San Diego, Calif., a corporation of California

Filed Nov. 9, 1966, Ser. No. 4,663

Term of patent 14 years

(Cl. D3—9)

The only figure is a perspective view of an applique emblem showing my new design. The applique emblem is of conventional thickness.

I claim:

The ornamental design for an applique emblem or similar article, substantially as shown and described.
